LUGGAGE LOCK

Louis M. Dyson, New Britain, Conn., assignor to
The American Hardware Corporation, New
Britain, Conn., a corporation of Connecticut

Application April 15, 1948, Serial No. 145,733

Term of patent 3½ years

(Cl. D50—7)

To all whom it may concern:

Be it known that I, Louis M. Dyson, a citizen of the United States, residing at New Britain, in the county of Hartford and State of Connecticut, have invented a new, original, and ornamental Design for a Luggage Lock, of which the following is a specification, reference being had to the accompanying drawing, forming part thereof.

Fig. 1 is a front view of a luggage lock, embodying my new design.

Fig. 2 is a side view thereof.

Fig. 3 is a side view showing the lock in open position.

Fig. 4 is a perspective view of said lock.

I claim:

The ornamental design for a luggage lock, substantially as shown and described.

LOUIS M. DYSON.
